(57) **CLAIM**

I claim the ornamental design for a headset, as shown and described.

DESCRIPTION

FIG. 1 is a Perspective view of a headset showing my new design;

FIG. 2 is a front view thereof;

FIG. 3 is a back view thereof;

FIG. 4 is a right-side view thereof;

FIG. 5 is a left-side thereof;

FIG. 6 is a top view thereof; and,

FIG. 7 is a bottom view thereof.

The broken lines are only for environmental purposes and form no part of the claimed design.

1 Claim, 7 Drawing Sheets
